A. C. ANDERSEN

ROTARY SPINDLE LOCK

Filed Dec. 17, 1921

INVENTOR.

Andrew Christian Andersen.

BY

Stuart S. Barnes

ATTORNEY.

UNITED STATES PATENT OFFICE.

ANDREW CHRISTIAN ANDERSEN, OF DETROIT, MICHIGAN, ASSIGNOR TO TERNSTEDT MANUFACTURING COMPANY, OF DETROIT, MICHIGAN, A CORPORATION OF MICHIGAN.

ROTARY-SPINDLE LOCK.

Application filed December 17, 1921. Serial No. 522,986.

To all whom it may concern:

Be it known that I, ANDREW CHRISTIAN ANDERSEN, a citizen of the United States, residing at Detroit, in the county of Wayne and State of Michigan, have invented certain new and useful Improvements in Rotary-Spindle Locks, of which the following is a specification.

This invention relates to locks and latches and especially to locks for vehicle doors. This is a rotary vertical spindle lock. Locks of this character are not broadly new. The improvement resides in the arrangement of the spindle in the case and in the stamped bolt which is provided with a cam follower or roll-back abutment.

In the drawings,—

Fig. 1 is a rear elevation of the lock.

Fig. 2 is an elevation of the lock showing the back plate removed.

Fig. 3 is a section on the line 3—3 of Fig. 5.

Fig. 4 is a section on the line 4—4 of Fig. 5.

Fig. 5 is a side elevation of the stamped bolt.

Fig. 6 is a fragmentary bottom or edge elevation of the lock case.

Fig. 7 is a perspective of the chair which helps to form the roll-back abutment.

a designates the face plate; *b* the front plate and *c* the back plate of the lock case. The back plate is vertically corrugated as is also the front plate to form grooves *d* and *e* to act as bearings for the rotary vertical spindle *f*, to the top of which is attached a turn handle or crank *h*. This vertical spindle *f* has a crank throw or roll-back *g* bent out near the bottom and the back plate is slotted as at *i* to accommodate this throw. The edges of this slot engaging with the throw holds the vertical spindle *f* from longitudinal movement.

The back plate is provided with lugs *j* which protrude through the openings *k* in the face plate and tapered pins *2* may be driven through perforations *m* in these lugs to hold the back plate assembled to the front plate. Or the lugs may be turned over to lock the two plates together. The back plate is provided with a perforation *n* in which is journaled the hub *o* of the outside roll-back *l*. *q* designates a hole in the rear plate for journaling the lock barrel spindle.

A special feature of this construction is

the bolt. This bolt has a head *p* to which is fastened the stamped body portion *r*. The construction of the head and the stamped body is not claimed in this application but in a co-pending application, Ser. No. 522,210, 60 for this bolt construction is of general application and is not limited to a rotary vertical spindle lock. However, the construction of the cam follower or the roll-back abutment *s* is new and has special application to a rotary vertical spindle lock. Referring to Fig. 2, a plan view of the bolt will be seen. This bolt comprises a head *p* cut from a hot-rolled bar and which is spot-welded onto the stamping *r*. This stamping is provided with an outside roll-back abutment *t* in the shape of a C. At the rear of the stamping ears *u* are turned up at each side and at the rear of these ears are slots *v*.

A peculiar insert and stamping, shown in perspective in Fig. 7, is adapted to be set in between these ears *u*. This stamping forms a chair *x* provided with a back *y* and a seat *z*. Legs *10* are provided at the front and these are adapted to be dropped into the recesses *v* and to be turned under to lock the legs to the stamping *r* (Fig. 3). Key lugs *20* are provided at the rear of the chair that are adapted to slip in appropriate key notches at the bases of the ears *u* to lock the chair to the turned-up ears. Hence when the key lugs are slipped into the notches and the legs of the chair are turned down, the chair is locked to the main body of the bolt at four places.

The main object of the construction described is to provide a bolt which is largely a stamping and therefore very much cheaper to manufacture and a better production article than a casting or forging.

What I claim is:

1. In a rotary vertical spindle lock, the combination of a case, a vertical rotary spindle journaled in the case and having a crank throw portion, and a sliding bolt reciprocated by said crank throw portion and comprising a body in the form of a stamping, and a chair in the form of a stamping which is secured to the body and is arranged to act as a roll-back abutment to be engaged by said crank throw.

2. In a rotary vertical spindle lock, the combination of a case, a rotary vertical spindle journaled in the case, a sliding bolt retracted by said spindle and provided with a

body portion in the form of a stamping, and a chair portion provided with portions adapted to lock into the stamping of the body portion to form a roll-back abutment 5 engaged by the vertical spindle to retract the bolt.

3. In a rotary vertical spindle lock, the combination of a case, a rotary vertical spindle journaled in said case, and a bolt slid-
10 ably guided in said case and having a body in the form of a stamping provided with side recesses, and a chair in the form of a stamped folded strip having turned-down legs adapted to engage in the recess of the
15 stamped portion to lock the chair to the body of the bolt and form a roll-back abutment engaged by the rotary spindle to retract the bolt.

4. In a rotary vertical spindle lock, the combination of a case, a rotary vertical spindle journaled in the case, and a bolt slidable in the case and provided with a body portion provided with recesses cut in the sides, and a chair in the form of a stamped folded
25 strip provided with key lugs adapted to lock into the stamped body of the bolt to secure the chair in place to form a roll-back abutment to enable the rotary spindle to retract the bolt.

30 5. In a rotary vertical spindle lock, the combination of a case, a rotary vertical spindle journaled in the case and a bolt guided in said case and provided with a stamped body having recesses cut in from the sides, and a chair in the form of a stamping or
35 folded strip provided at the front corners with turned-down legs that are adapted to be clamped in the recess of the stamped body and provided at the rear corners with key lugs adapted to engage in portions of the stamped body of the bolt, said chair forming a roll-back abutment engaged by the spindle to retract the bolt.

40 6. In a rotary vertical spindle lock, the combination of a case; a rotary vertical spindle journaled in the case, and a bolt slidable in the case and provided with turned-up ears at the sides, and a chair comprising a folded strip adapted to engage against the turned-up lugs and complement the same to form a roll-back abutment engaged by a portion of the rotary spindle to retract the bolt.

45 7. In a rotary vertical spindle lock, the

combination of a case, a rotary vertical spindle journaled in the case, and a sliding bolt 55 guided in the case provided with a stamped body portion having turned-up ears at the sides and with recesses cut in adjacent said turned-up lugs, and a chair comprising a folded strip adapted to fit between the folded-
60 up ears and having a back arranged to complement the ears and abut against the same and provided with turned-down legs adapted to be clamped in the recesses of the body of the bolt whereby a roll-back abutment is 65 formed.

8. In a rotary vertical spindle lock, the combination of a case, a rotary vertical spindle journaled in the case, and a bolt slide-
70 ably guided in the said case and guided therein having a body in the form of a stamping having at the sides turned-up ears and recesses adjacent the lugs, said turned-up ears provided at their bases with key notches, and a chair com-
75 prising a folded strip adapted to fit between the ears with the chair back abutting the front edges of the ears and provided with key lugs adapted to fit into the key notches of the turned-up ears and provided at the front of the chair with turned-down legs that can be clamped in the recesses to secure the chair in place and form a roll-back abutment against which a portion of the rotary spindle operates to retract the bolt.

9. In a rotary vertical spindle lock, the combination of a casing including a front plate, a back plate, one of which is provided with a vertical corrugation, the other pro-
80 vided with a pressed in portion having a vertical corrugation pressed out from a part of said pressed in portion, the said corrugations arranged to match together to form spindle bearings, a vertical spindle journaled in said matching corrugations, and a sliding lock recipro-
85 cated by said vertical spindle.

10. In a rotary vertical spindle, the combination of a casing including a front plate, a back plate, said plates provided with pressed in channel portions having vertical matching corrugations pressed out from said pressed in channel portions to form spindle bearings, a vertical spindle journaled in said corrugations, and a sliding lock reciprocated by said vertical spindle.

In testimony whereof I affix my signature.

ANDREW CHRISTIAN ANDERSEN.
